(57) **CLAIM**

The ornamental design for a “rotating shaft assembly,” as shown and described.

DESCRIPTION

FIG. 1 is a front perspective view of a rotating shaft assembly;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion 9 in FIG. 1;

FIG. 10 is an enlarged view of portion 10 in FIG. 2; and,

FIG. 11 is an enlarged view of portion 11 in FIG. 2.

The broken lines represent portions of the rotating shaft assembly that form no part of the claimed design. The reference numerals 9, 10 and 11 and its associated leader line and enclosure in FIGS. 1, 2, 9, 10 and 11 form no part of the claimed design.

1 Claim, 11 Drawing Sheets
